CLAIM

The ornamental design for a square drive wrench having angled head, as shown and described.

DESCRIPTION

FIG. 1 is a right side elevation of a square drive wrench having angled head of the present invention;
FIG. 2 is a left side elevation of the wrench;
FIG. 3 is a top plan of the wrench;
FIG. 4 is a bottom plan of the wrench;
FIG. 5 is a front elevation of the wrench; and,
FIG. 6 is a rear elevation of the wrench.
